UNITED STATES PATENT OFFICE.

WALTER MYERS, OF BRIDGEPORT, CONNECTICUT, ASSIGNOR TO THE SINGER MANUFACTURING COMPANY, A CORPORATION OF NEW JERSEY.

TRIMMING-SUPPLY-CONTROLLING DEVICE FOR EMBROIDERING-MACHINES.

1,325,034.

Specification of Letters Patent. Patented Dec. 16, 1919.

Application filed April 9, 1918. Serial No. 227,442.

To all whom it may concern:

Be it known that I, WALTER MYERS, a citizen of the United States, residing at Bridgeport, in the county of Fairfield and 5 State of Connecticut, have invented certain new and useful Improvements in Trimming-Supply-Controlling Devices for Embroidering-Machines, of which the following is a specification, reference being had therein 10 to the accompanying drawings.

This invention relates to an improvement in sewing machines for embroidering, especially to those employed for sewing to a body-fabric ornamenting trimmings such as 15 braids, tapes, edgings, ribbons and the like.

Sewing machines of this character ordinarily include stop-motion devices automatically operative to stop the machine at the completion of each stitch and with the needle 20 out of the work, but which may be manually rendered ineffective during the formation of any desired number of stitches. Whenever the machine was stopped with the needle out of the material in machines employing 25 a trimming unwinder bodily rotatable around the needle-bar, the spool or reel forming the trimming supply invariably overran itself, thereby loosening an undesirable quantity of improperly controlled 30 trimming between the supply and the needle. This defect is not overcome by the provision of a constant tension on the trimming, for in certain classes of work it is undesirable to have any tension on the trimming during 35 the period of stitch-formation.

The present invention has for its primary object to provide a construction obviating any tendency of the trimming supply to overrun itself upon the stopping of the machine, but to nevertheless properly control the trimming during the feeding action of 40 the machine.

To the attainment of these ends there is embodied in the sewing machine a supply- 45 reel for the trimming mounted for bodily rotating movement to accord with the direction of feed and including a trimming-supporting spindle adapted to rotate during the unwinding of the trimming. Mounted 50 to rotate with the spindle is a checking- or click-disk having a notched periphery adapted to be yieldingly engaged during the feeding of the material by a spring-pressed finger on one arm of a two-armed lever ful- 55 crumed on a trimming-reel supporting

bracket. The other arm of the lever is adapted to be acted upon by a cam-roller carried by the needle-bar in such wise as to permit the spring to act upon the lever to check the trimming when the needle is out 60 of the material, during which time the feeding of the fabric occurs when the machine is in operation and which is also the stopping position of the machine. During the time the needle is in the material, the cam- 65 roller acts upon the two-armed lever to release the checking disk, a condition essential to certain classes of work.

In the accompanying drawings Figure 1 is a front side elevation, partly in section, 70 of a sewing machine embodying the present improvement. Fig. 2 is a top-plan view of the trimming reel and its supporting bracket, with the trimming carrying spindle partly broken away. Fig. 3 is a fragmentary view of the checking disk and finger.

Referring to the drawings, the sewing machine is constructed with a cloth-plate 1, from which rises the vertical standard 2 of the overhanging bracket-arm 3, terminat- 75 ing in the head 4 to which is suitably secured the needle-bar and feed-supporting frame 5. Journaled in suitable bearings provided in the overhanging arm is the main or driving shaft 6.

The frame 5 is formed with parallel, horizontally extending bearing brackets 7 and 8, having vertically aligned apertures in which is journaled for rotary movement the cylinder 9, carrying the needle-bar, feed and 80 trimming supporting and guiding elements.

Mounted for vertical reciprocating movements in the cylinder 9 is the needle-bar 10, carrying the needle 11 and constrained in the usual manner to rotate with the cylinder. 85 Secured to the needle-bar and slidably mounted upon the cylinder is the peripherally grooved collar 12 embraced by the forked end of the arm 13 projecting from the usual needle-bar driver, vertically slid- 100 able in ways formed in the frame 5 and reciprocated in a well known manner from the driving shaft 6. Any well known form of looper mechanism may be employed to cooperate with the needle in the formation of 105 stitches.

The cylinder 9 is adapted to be manually rotated to obtain the desired direction of feed by means of a hand-crank 14 carried by a crank-arm 15 secured to a crank-shaft 110

16 journaled in a bearing provided in the bracket 17 suitably secured to the under side of the cloth-plate. The crank-shaft 16 through intermeshing gears actuates a shaft 5 18 which in a similar manner actuates a shaft 19, both of which shafts are journaled in the bracket 17. The shaft 19 at its rearward end, through intermeshing gears, drives a vertical shaft 20, which in a similar 10 manner actuates a horizontal shaft 21, journaled in the overhanging bracket-arm. The shaft 21 at its forward end carries a gear-member 22 in mesh with a gear-member 23 rotatably supported upon a stud-shaft 24 15 upon the frame 5. Mounted to rotate with the gear-member 23 is a bevel-gear 25 in mesh with a similar gear 26 suitably secured upon the cylinder 9.

As usual in machines of this class, there is 20 provided a stop-motion device adapted to automatically stop the machine after the completion of each stitch unless manually prevented from operating. The stop-motion device disclosed in the accompanying drawings 25 is of well known construction, the several parts thereof being designated by the reference character *m* and constructed substantially as shown and described for instance in the United States patents to A. 30 Bonnaz, No. 83,910, dated November 10, 1868 and to E. Cornely, No. 182,804, dated October 3, 1876.

The feeding mechanism includes a feeding foot *f* capable of being manually controlled 35 under the action of the hand-crank 14 to feed the material in any desired direction in a single plane and as, for the purposes of this invention, any well known form of universal feeding mechanism such as is disclosed 40 for instance in the United States patent to D. Noble, No. 1,049,520, dated January 7, 1913, may be employed, it is deemed unnecessary to enter into a detailed description of the feeding mechanism partly 45 disclosed in the accompanying drawings.

The upper end of the cylinder 9 is formed with a flange 27 to which is secured a supporting disk 28 carrying the trimming supply holder and the needle-thread holders 50 and guides. To the disk 28 is suitably secured a supporting bracket 29 carrying a trimming supporting spindle 30 adapted to rotate with the trimming during the unwinding thereof. Secured to the spindle is a 55 checking or click-disk 31 having a notched periphery adapted to be yieldingly engaged by a checking finger 32 forming one arm of a lever fulcrumed upon the bracket 29 by means of a pivot-screw 33. This arm of the 60 lever is acted upon by a spring 34 positioned in a socket in the bracket 29 and acting when permitted to cause the checking finger to engage the notched periphery of the checking disk. The other arm 35 of the lever is 65 adapted to be engaged by a roller 36 carried

by a collar 37 suitably secured to the upper end of the needle-bar. The inclination of the arm 35 relative to the needle-bar when the latter is at its upper position is due to the action of the spring 34. When the machine is stopped with the needle out of the material, the checking disk 31 is prevented from overrunning by the action of the finger 32. Further as the feed of the material occurs when the needle is out of the material, the trimming is properly controlled during the feeding action. When the needle-bar descends and penetrates the material, that is, during the return movement of the feeding member, the finger 32 is positively removed 70 from contact with the disk, thereby freeing the latter from tension, a condition essential to certain classes of work during the formation of stitches. The trimming is led from its unwinder through either of the 75 apertured ears, as 38, thence through the hollow cylinder 9 and to the usual braid-guide 39.

The supporting disk 28 further carries a spool-pin 40 for the needle-thread spool, 80 a tension device 41 including a thread-controlling spring 42 and thread-guiding posts 43, 44 and 45. The needle-thread is led around the bracket 29, through the tension device 41, around the post 43, through an aperture in the end of the spring 42, thence through openings in the posts 44 and 45, respectively, through an aperture in the collar 37 and downwardly through the hollow needle-bar to the needle. This manner of 90 leading the thread to the needle, permits the needle-bar, in its reciprocations, to pull off the necessary supply of thread and set the stitches.

Having thus set forth the nature of the 105 invention, what I claim herein is:—

1. In a sewing machine, in combination, 110 stitch-forming mechanism including a reciprocable needle-bar, a needle carried by said needle-bar, a trimming supply-holder bodily rotatable around said needle-bar, and means brought into action when the operation of the machine is arrested for checking the trimming supply and to prevent overrunning of the same.

2. In a sewing machine, in combination, 115 stitch-forming mechanism including a reciprocable needle-bar, a needle carried by said needle-bar, a trimming supply-holder bodily rotatable around said needle-bar, a stop-motion device adapted to bring the machine to rest with the needle out of the material, means brought into action during the stopping of the machine to check the rotation of the trimming supply and prevent overrunning of the same, and means for releasing said trimming supply on the initial downstroke of the needle-bar of a 120 succeeding stitching operation.

3. In a sewing machine, in combination, 125

stitch-forming mechanism including a reciprocable needle-bar, a needle carried by said needle-bar, feeding mechanism including a feeding member having fabric feeding 5 and return movements, a trimming supply, means for checking the supply against overrunning during the fabric feeding action of said feeding member, and means for releasing said trimming supply during the return 10 movement of said feeding member.

4. In a sewing machine, in combination, stitch-forming mechanism including a reciprocable needle-bar, a needle carried by said needle-bar, a trimming supply, a stop- 15 motion device adapted to bring the machine to rest with the needle out of the material, means brought into action during the stopping of the machine to check said trimming supply and prevent overrunning of the 20 same, and means carried by said needle-bar for releasing said trimming supply.

5. In a sewing machine, the combination with stitch-forming mechanism including a reciprocable needle-bar, a needle carried by 25 said needle-bar, of a trimming supply-holder including a rotatable trimming-supporting spindle, a checking disk rotatable with said spindle, and a checking finger adapted to yieldingly engage said disk and 30 intermittently check the trimming supply during the operation of the machine.

6. In a sewing machine, the combination with stitch-forming mechanism including a reciprocable needle-bar, a needle carried by 35 said needle-bar, of a trimming supply-holder including a trimming-supporting spindle, a checking disk rotatable with said spindle, a checking finger adapted to yieldingly engage said disk to check its rotation, 40 and means carried by said needle-bar for releasing said checking finger.

7. In an embroidering machine, the combination with stitch-forming mechanism in-

cluding a vertically reciprocable and axially rotatable needle-bar, a needle carried by 45 said needle-bar, and feeding mechanism adapted to feed a material being acted upon in any direction in a single plane, of a trimming supply-holder bodily rotatable to accord with the direction of feed, an axially 50 rotatable trimming-supporting spindle, a checking disk rotatable with said spindle, a checking finger adapted to yieldingly engage said disk to check its rotation, and positive means for releasing said checking 55 finger.

8. In an embroidering machine, the combination with stitch-forming mechanism including a vertically reciprocable needle-bar, a needle carried by said needle-bar, a cylinder upon which said needle-bar is adapted to reciprocate, feeding mechanism, and means for rotating said cylinder to change the direction of feed, of a trimming supply-holder supported by said cylinder and 60 bodily rotatable around said needle-bar, a rotatable checking disk, a finger adapted to yieldingly engage said disk to check its rotation, and means for releasing said finger.

9. In an embroidering machine, the combination with stitch-forming mechanism including a vertically reciprocable needle-bar, a needle carried by said needle-bar, a cylinder in which said needle-bar is adapted to reciprocate, feeding mechanism, and means 70 for rotating said cylinder to change the direction of feed, of a trimming supply-holder supported by said cylinder, a rotatable checking disk having a notched periphery, a finger adapted to yieldingly engage the notched periphery of said disk to check its rotation, and means carried by the 75 needle-bar for releasing said finger.

In testimony whereof, I have signed my name to this specification.

WALTER MYERS.
